COMPANY OF THE NETHERLANDS.

DRAWING FRAME.

Application filed June 19, 1928, Serial No. 286,510, and in Czechoslovakia June 27, 1927.

This invention relates to a drawing frame for spinning machines which differs from known drawing frames by single- or double-sided roving condensers which rest 5 loosely on the upper rollers, these condensers preferably not having driving means, but being provided free to slide to and fro on the roller with the roving passing through the condenser.

10 The object of this roving condenser is not only to condense the fibres of the preliminarily drawn roving but also to keep the rollers clean and thereby prevent the roving from adhering to the small rollers.

15 In the drawing:

Figure 1 shows by way of example a construction of a drawing frame in side elevation, whilst

20 Figure 2 shows in perspective the arrangement of the roving condenser, and

Figures 3 and 4 illustrate in perspective the condenser in two constructions.

It is assumed as known, that the drawing frame is constituted by fluted cylinders or 25 rollers 1, 2, 3, 4 and 5, each of which operates with a top roller 6, 7, 8, 9 and 10.

The roving is introduced (single or doubled) to the feed roller 5 and transmitted by the latter between the cylinders 4 and 9 30 to the cylinders 3 and 8. The roving which is partly preliminarily drawn is transmitted by the cylinder 3 to the pair of rollers 2, 7. From the pair of rollers 2, 7 the roving passes between the rollers 1, 6, starting from 35 which the twisting of the finely drawn roving for the purpose of forming yarn is effected by the spindle in the usual manner.

The weighting of the two top rollers 6 and 8 is effected by means of a joint saddle 40 15, the hook 14 of which is bent out rearwardly.

According to the invention, the roving condensers 12 (Figures 1 and 2) overlap the rollers and are constituted by an arc 45 shaped rider, the arc of which is adapted to the diameter of the upper roller. According to Figures 2 and 3, the arc is provided at one side with extensions 16 which leave between them a slot 17 which is widened 50 out into a circle at its end 18. A handle 19 is preferably stamped out in the arc of the condenser by means of which the condenser may be introduced quite simply into

the drawing frame and removed from the same.

55 In the construction shown in Figure 4, the roving condenser is provided with extensions 16, 16' at both sides of the arc.

These roving condensers lie loosely on the upper roller, they are not driven and are 60 not held in any other way on the rollers. The roving condensers only follow the lateral movement of the roving which is given its movement in a known manner by a guide 13. The roving condensers are chiefly intended for condensing rovings which are 65 already preliminarily drawn and at the same time they keep the roller clean, owing to which, more particularly on rollers of small diameter, adherence of the roving, which 70 is exceedingly injurious, is avoided.

1 claim:

1. In a drawing mechanism the combination with a pair of co-operating upper and lower rollers through the nip of which a 75 roving may pass of a hook-shaped plate loosely hanging upon the upper roller and having a slot in its depending portion through which the roving may pass to the nip of the rollers.

80 2. In a drawing mechanism the combination with a pair of upper and lower rollers through the nip of which two spaced rovings may pass of a pair of hook-shaped plates hanging upon the upper rollers, the 85 two hook-shaped plates each having a slot in its depending portion through which a roving may pass to the nip of the rollers.

3. In a drawing mechanism, the combination with a pair of upper and lower rollers 90 through the nip of which a roving may pass of an inverted U-shaped plate loosely hanging on the upper roll, the depending portions of the said plate each having a slot therein, through which slots the roving may 95 pass to and away from the nip of the rollers.

4. In a drawing mechanism the combination with a pair of upper and lower rollers through the nip of which a roving may pass, of a pair of inverted U-shaped plates, each 100 of the said plates hanging on the upper roll, each of the depending portions of both said plates having a slot through which slots rovings may pass to and out of the nip of the rollers.

105 5. For use in a drawing mechanism com-

prising a pair of drawing rollers, a metal plate having one end bent to form a hook to hang freely upon the upper roller, the other end being straight and provided with a slot extending inwardly from the said end.

6. For use in a drawing mechanism comprising a pair of drawing rollers, a metal

plate bent to a U-shape to hang freely upon the upper roller the ends of the plate being straight and provided with inwardly extending slots.

In testimony whereof I have signed my name to this specification.

RUDOLF NIGRIN.
